WINDOW CONSTRUCTION

James W. Batts, Beaumont, Tex., assignor to Permanent Glaze, Inc., Beaumont, Tex., a corporation of Texas

Application January 2, 1957, Serial No. 632,152

6 Claims. (Cl. 20—56.4)

This application is a continuation-in-part of my co-pending application, Serial No. 524,650, filed July 27, 1955, now abandoned.

The present invention relates to window constructions and particularly to novel means for mounting a pane of glass in a window frame.

A principal object of the invention is to provide a novel window pane retaining strip adapted to be conveniently attached to a window frame in locking engagement with the pane.

Another object is to provide a window pane retaining strip of resilient sheet metal construction adapted to be anchored in a window frame and engage a window pane at a plurality of regions thereon.

A further object resides in the provision of an inexpensive window pane retaining strip facilitating glazing operations.

A still further object is to provide a novel window construction utilizing a window pane retaining strip engaging the pane and the frame in such a manner that the strip and pane will be effectively locked against removal. A related object is to design the strip so that a sealing means applied between the strip and the pane will be desirably protected from external elements.

An additional object is to provide a novel waterproof window construction characterized by superior water-shedding or water tight characteristics.

Further objects and advantages of the invention will be in part obvious and in part pointed out hereinafter.

The novel features of the invention may be best made clear from the following description and accompanying drawings in which:

Figure 1 is a fragmentary, perspective view of a window construction embodying the invention;

Figure 2 is a vertical sectional view of the construction of Figure 1;

Figure 3 is a perspective view of one form of window pane retaining strip of the invention;

Figure 4 is a front elevational view of the window construction;

Figure 5 is a fragmentary, perspective view of another form of window construction embodying the invention;

Figure 6 is a vertical sectional view of the sill part of the construction of Figure 5, and

Figure 7 is a perspective view of a modified form of pane retaining strip.

Referring now to Figures 1-3 of the drawings, the embodiment of my invention disclosed in the aforesaid co-pending application, Serial No. 524,650, includes a window pane retaining strip 10 adapted to be connected to a frame part or rail of a window construction, as the sill part 12, and engageable with a window pane 14.

The strip 10 preferably is formed of integral, resilient or flexible sheet metal, such as aluminum, including a longitudinally extending leg portion 16 joined to an inclined planar portion 18 defining with leg 16 an obtuse interior angle. The upper end of planar portion 18 defines a first pane-engageable portion 20 and preferably is

2

reversely bent rearwardly and downwardly into a concave portion 22 defining a groove for the reception of a sealing means. The lower part of concave portion 22 constitutes a second pane-engageable portion 24 and the strip 10 preferably is formed so that the first pane-engageable portion 20 is disposed farther from the top of leg 16 than it is from the second pane-engageable portion 24.

The window frame including sill part 12 may be constructed of any suitable material, such as metal or wood, and part 12 includes the usual window pane engaging shoulder 26 and ledge 28 extending laterally outwardly therefrom. Ledge 28 preferably is formed with a longitudinal groove 30 therein adjacent the outer end thereof.

The preferred manner in which strip 10 is utilized to glaze a window frame will now be described. The pane 14 is first mounted within the window frame against the peripheral abutment shoulder 26 thereof, and the leg 16 of strip 10 is fitted into the groove 30, as indicated by 15 the successive dotted and solid line positions of the strip 20 illustrated in Figure 2, this fitting or insertion of the leg 16 in the groove 30 being facilitated by the resiliency of the strip. By virtue of the relative dispositions of the 25 various portions of the strip 10, it will be appreciated that the first pane-engageable portion 20 will frictionally bear against the pane 14 along a line or in a region disposed inwardly from the outer edge of the pane, the second pane-engageable portion 24 of the strip will be disposed in a position outwardly of the outer edge of the pane 14, 30 but in pressure contact therewith, and the leg 16 will be firmly anchored in groove 30.

It will be evident that after the strip 10 has been attached to the window frame in the above manner, the groove formed by the concave portion 22 thereof will 35 be completely enclosed by the engagement of the strip 10 with pane 14, whereby caulking material 23 or a sealing gasket may be arranged in this groove and be protected from the deteriorating effects of external elements.

A window frame 32, glazed by means of strips 10 of 40 the invention, is illustrated in Figure 4 and includes a sill or bottom part 12, as well as jamb 34 and head 36 parts, preferably of the same transverse cross-sectional configuration as sill part 12, to define a peripheral shoulder 26 and peripheral ledge 28. It will be appreciated that it is not necessary to have the groove 30 in each frame part align perfectly with the grooves of the remaining parts. A strip 10 is arranged in each of the frame parts in the manner previously described for sill part 12 and the invention contemplates a novel arrangement of the ends of the strips 10 for preventing water 45 from leaking through the joints of the window. A preferred form of this arrangement includes the following structure at the ends of strips 10. The strip 10 fitted into the sill part 12 preferably includes squared or straight ends 38 disposed parallel to and engaging the ledge 28 of the adjacent jamb parts 34. The strips 10 connected to the jamb parts 34 preferably include mitered or beveled lower ends 40 fitting over or lapping the adjacent ends 50 of the strip 10 in sill part 12; while the upper ends 42 of the strips 10 for jamb parts 34 are squared for engagement to the ledge 28 of the head part 36. The strip 10 in the head part 36 includes mitered or beveled ends 44 fitting over or lapping the adjacent ends of the strips in the jamb parts 34. Thus, it will be seen that 55 any rain or other precipitation striking the window in any direction will be desirably shedded by the strips 10. These various strips 10 preferably are attached in operative position in the same order in which their end structures were described.

An outstanding advantage of the strip 10 is that once 60 it is arranged in pane retaining position, it will be securely retained in this position due to the resiliency

thereof and the manner in which it engages the frame 32 and pane 14. When leg 16 of each strip is anchored in the groove 30, the first portion 20 will be firmly resiliently urged against pane 14 and in addition, the weight of the glass pane 14 on the second portion 24 of strip 10 in the sill part 12 will tend to deform or deflect the concave portion 22, thereby enhancing this friction engagement of first portion 20. The portions 24 for the strips 10 in the jamb 34 and head 36 parts will also be in pressure contact with the adjacent edges of the pane. It will be evident that any attempts to remove the strip 10 from its operative position, such as by pulling outwardly on the planar portion 18 or portion 20 thereof, will tend to distort the concave portion 22 in such a manner that the second pane-engaging portion 24 will be more tightly and firmly pressed inwardly against the outer edge of the pane 14, thereby effectively resisting and preventing removal of the strip.

Another embodiment of the invention is illustrated in Figures 5 through 7, wherein the parts of the window corresponding to similar parts of the Figures 1-4 embodiment are identified by similar reference numerals. The pane retaining strip 10' in Figures 5-7 preferably is also formed of integral, resilient sheet metal and is connected to a window frame 32' for retaining the pane 14' therein. As in the case of window frame 32, all of the parts of frame 32' preferably are formed of identical transverse sectional configuration, and include the pane-engaging shoulder 26' and ledge 28' extending laterally outwardly therefrom. In this embodiment, however, an inner, strip-receiving, longitudinal groove or channel 46 is formed in the ledge 28' of the frame part adjacent the juncture of the ledge 28' and shoulder 26' (Figure 6). This groove 46 preferably is of inclined V-shape in cross-section having a rear or back vertical surface, and the outer groove 30' in the ledge 28' preferably is also of inclined V-shape in cross-section, but with a forward or front vertical surface.

The strip 10' includes the leg 16', and planar portion 18' joined thereto and terminating at its upper end in the first pane-engageable portion 20'. The concave portion 22' depending from portion 20' preferably merges into the lower, second pane-engageable portion 24', the free or outer end of the latter portion may be disposed approximately the same distance from first portion 20' as the top of leg 16'.

To glaze the frame 32', the pane 14' is arranged therein against the peripheral shoulder 26' and the strips 10' may be attached to each of the frame parts in the following manner. The leg 16' is fitted into the outer groove 30' and the strip 10' is moved through the successive positions indicated in dotted and solid lines in Figure 6 until the second pane-engageable portion 24' is disposed in the groove 46 at which time the leg 16' will bear firmly against the vertical surface of its groove 30'. Additionally, the portion 24' will now be pressed firmly against the forward portion of the outer edge of pane 14' and the portion 20' will be pressed firmly against the pane 14' at a region inwardly of the edge. The outer groove defined by the concave portion 22' for the reception of a sealing means will be enclosed by the pane 14' in the engaged regions of the latter, in the same manner as that described for strip 10. The ends of the strips 10' for each of the parts of window frame 32' preferably will be formed in the manner of the aforescribed embodiment for endowing frame 32' with desirable water-shedding characteristics.

It will be appreciated, that in addition to all of the advantages of the previously described, Figures 1-4 embodiment, the strip 10' is adapted to readily accommodate variations in the dimensions of the pane 14' without sacrificing any of its locking characteristics, and also without necessitating alteration. Stated differently, the strip 10' may be conveniently and expeditiously arranged in pane retaining position whether the pane 14' fits substantially

exactly into the juncture of the angulated peripheral recess formed by shoulder 26' and ledge 28' of each frame part or whether the pane 14' is somewhat smaller than the size required for exact fit in such recess.

5 It will be evident that the transverse distance between the bottom of leg 16' and the free end of portion 24' of strip 10', in normal detached position, may be somewhat greater than the corresponding transverse distance between the bottoms of grooves 46 and 30' whereby portion 24' and leg 16' will be deformed or deflected relatively toward each other when the strip is arranged in operative position. Such deflection improves the locking action of the strip by increasing the pressures in the three principal locking regions, namely, leg 16', portion 29' and portion 24'.

10 It will thus be seen that the objects of this invention have been fully and effectively accomplished. It will be realized, however, that the foregoing specific embodiments have been shown and described only for the purpose of 20 illustrating the principles of the invention and are subject to extensive change without departure from such principles. Therefore, this invention includes all modifications encompassed within the spirit and scope of the appended claims.

15 I claim:

1. In an article of the character described, a wooden window frame having a peripheral abutment surface, a window pane arranged against and in direct contact with said surface, a peripheral groove formed in said frame and spaced laterally from said abutment surface, said groove extending in a direction generally parallel to said abutment surface, and a plurality of window pane retaining resilient strips, said strips including: a leg fitted into said groove, a first portion joined to said leg and 30 resiliently pressing directly against and in contact with the window pane at a point inwardly of an outer edge of the pane, and a second portion joined to said first portion and spaced from said leg, said second portion terminating in a free end disposed outwardly of the window pane and substantially in the same plane therewith, and said second portion resiliently pressing against and engaging the outer edge of the window pane and extending from said pane edge toward said abutment shoulder.

2. The structure defined in claim 1 wherein said strips are of integral metallic construction; and a longitudinally extending concave portion being formed between said first and second portions for the reception of a sealing means.

3. The structure defined in claim 2 wherein said leg is planar and is joined to said first portion by a planar portion inclined with respect to said leg.

4. The structure defined in claim 3 wherein the first portion is disposed approximately equidistantly from the top of the leg and the second portion, said frame including a second peripheral groove intermediate the abutment surface and the first-named groove, and said second portion being fitted into said second groove.

5. The structure defined in claim 3 wherein the first portion is disposed farther from the top of the leg than it is from the second portion, said second portion extending in contact with an outer edge of the window pane throughout substantially the entire width of the edge.

6. In an article of the character described: a rectangular window frame having interconnected top, bottom and jamb parts defining a rectangular window pane receiving opening, a longitudinal angulated recess in each of said parts defining a peripheral abutment surface and a ledge 70 perpendicular thereto adjacent said opening, said peripheral ledge having a coextensive groove formed therein, said groove extending in a direction generally parallel to said abutment surface; a window pane being arranged against said abutment surface; a plane retaining resilient strip for each of said frame parts, each of said strips

including a leg fitted into said groove, and first and second portions joined to said leg and frictionally engaging said window pane respectively at an outer edge thereof and at a region disposed inwardly of said edge, said second portion extending from said pane edge toward said abutment surface, the strip connected to said bottom part having squared ends parallel to and engaging said jamb parts, the strips connected to said jamb parts having mitered lower ends fitting over the strip on said bottom frame part, and squared upper ends parallel to and 10

engaging said head part, and the strip connected to said head part having mitered ends fitted over the strips on said jamb parts.
